LIQUID FUEL PREPARING APPARATUS

Harry B. Holthouse, Jr., Chicago, Ill., assignor to
 Galvin Manufacturing Corporation, Chicago,
 Ill., a corporation of Illinois

Application April 7, 1943, Serial No. 482,100

5 Claims. (Cl. 158—28)

1

This invention relates generally to means for treating a liquid fuel for burning and in particular to such means for preparing a liquid fuel for burning in a heater of combustion type.

Many types of liquid fuel burners use electric heating systems having an electrical heater of resistance type for heating the fuel to be burned or for igniting the fuel for burning. These electric heaters are generally of coil type and in their operation the fuel is usually passed into direct contact with the coil. The fuel contacting the coil cools the same and also covers it with a film of soot so as to appreciably reduce its efficiency for heating purposes. Further the fuel contacting the coil sets up a corroding action which gradually destroys the coil. As a result the heat generated by the coil is retained within the coil so that the coil operates at temperatures in excess of those for which it is designed and soon burns out. Another factor which appreciably impairs the life and operation of these prior art heating coils arises by virtue of the location of the coil in a position where it is exposed to the flames of combustion. When the coil is thus exposed to the action of the flames it generally becomes heated above its normal operating temperature with such excess heat accelerating the corroding action of the fuel on the coil. All of these factors contribute materially to shortening the operating life of the coil and reducing the efficiency of its operation over the span of its service life.

It is an object of this invention, therefore, to provide an improved means for preparing a liquid fuel for burning.

Yet another object of this invention is to provide an electrical heater for preparing a liquid fuel for burning in which the liquid fuel is prevented from contacting the coil.

Another object of this invention is to provide a liquid fuel conditioning means which is simple and inexpensive in construction, efficient in operation to prepare a combustible air and fuel mixture of uniform characteristics, and in which an electric coil for preparing the fuel for mixing with the air functions as a combination heating and igniting unit without at any time coming into contact with the air and fuel mixture or being exposed to the flames of combustion.

A feature of this invention is found in the provision of a liquid fuel treating means in which an electric resistance for treating and igniting the fuel is supported in a spaced relation within a heat conducting tube having one end open to the flow of the treated fuel. Air under pressure

2

is passed through the tube at all times of coil operation to prevent the passage into the tube of any liquid or heated fuel for contact with the coil.

5 Further objects, features, and advantages of this invention will become apparent from the following description when taken in connection with the accompanying drawings in which:

Fig. 1 is a sectional view of a combustion type heater embodying the fuel treating means of this invention, with the combustion chamber of the heater being shown in development for the purpose of clarity;

Fig. 2 is an enlarged sectional detailed view of 15 the invention, which is indicated generally in Fig. 1 to show its relative assembly with the remainder of the heater;

Fig. 3 is a sectional view as seen along the line 3—3 in Fig. 1; and

20 Fig. 4 is a view in perspective of an insulating supporting member for a heating coil in the fuel treating means.

In practicing this invention there is provided 25 an air heating system of internal combustion type having an air and fuel mixing device in fluid connection with a combustion chamber. The mixing device includes a combination electric heater unit for conditioning the air and fuel to be burned and for igniting such air and fuel mixture for burning. The electric heater unit includes a heating element comprised of a single resistance coil supported in a spaced relation 30 within a heat conducting tube open at one end to the combustion chamber.

35 Air and fuel introduced into the mixing device are heated while passing about the heat conducting tube to vaporize the fuel for mixing with the air. The vaporous air and fuel mixture is directed into the effective igniting zone of the coil at

40 the open end of the tube for ignition. In order to eliminate any portion of the vaporous mixture from contacting the coil, with the deleterious results mentioned above, air is forced through the tube in a direction towards the open end, heated

45 to a temperature above the ignition temperature of the vaporous mixture, and then moves into the combustion chamber where it ignites the vaporous mixture. At no time, therefore, is the coil contacted by the fuel during either the heating

50 or igniting of the fuel so that all difficulties arising from the fuel contacting the coil are entirely eliminated. To further prolong the life of the heating coil the vaporous mixture on being ignited is immediately projected away from the coil for burning at some point away from the

coil. The coil is thus entirely out of the flames of combustion and not subjected to the intense heat of the burning mixture.

Referring to Fig. 1 of the drawings a heating unit embodying the liquid fuel conditioning means of this invention is seen to include a housing 10 which is divided longitudinally over substantially its entire length by a vertically extending partition member 11 to form a mechanical compartment 12 and a heating compartment for a combustion chamber 13. The combustion chamber, shown in development in Fig. 1 for the purpose of clarity, is closed at one end by a cover plate 14 and at its opposite end by the bottom 16 of a substantially cup shaped member 17 which defines in part an air supply chamber 18 in axial alignment with the combustion chamber 13. The combustion chamber 13 is divided longitudinally into four axially extending but connected passages 19a-19d by a partition member 21 of substantially X-shape (Figs. 1 and 3). An inlet 22 and an outlet 23 for the combustion chamber are formed in the bottom 16 of the cup shape member 17 in communication with the passages 19a and 19d, respectively. The liquid fuel treating means 24 of this invention, is located in the inlet 22 and extended within the air supply chamber 18. A tail pipe assembly 26 for carrying exhaust gases from the combustion chamber 13 is extended from the outlet 23 through the air supply chamber 18 and outwardly from the heater at the housing end 27.

The outer wall or body portion of the combustion chamber 13 carries angularly spaced axially extending fins 28. The fins 28 have a sleeve 29 positioned about their outer ends to form annular passages 31 about the combustion chamber 13 for air to be heated. The air to be heated is admitted into the passages 31 through an annular chamber 32 connecting these passages with the mechanical compartment 12 and is circulated about the combustion chamber through the passages 31 by a fan 33 located within the compartment 12 and mounted on a shaft 34 of an electrical motor 36. The compartment 12, chamber 32 and passages 31 are separated from the air supply chamber 18 by a partition member 37 extended transversely of the housing 10. Thus from Fig. 1 it is seen that the air supply chamber 18 is defined by the cup member 17, the partition member 37 and the end 27 of the housing 10. Air circulated by the fan 33 is thus confined for travel within the compartment 12 and passages 31 and is discharged from the passages 31 through an outlet 38 which is connected to a space to be heated.

The air supply chamber 18 receives air from a fan 39 mounted on the motor shaft 34 which is journaled in the partition plate 37, with an inlet 41 for the fan 39 being formed in the housing end 27. It is seen, therefore, that the fans 33 and 39 are operated by the motor 36 and mounted directly on the motor shaft 34. The motor 36 is also used in the operation of a fuel pump 42 which is illustrated as being of a solenoid type. A breaker assembly 43 for controlling the energization of the pump 42 is operatively associated with the motor shaft 34. Fuel for the pump 42 is supplied from a suitable source (not shown) through a pipe 44 and is delivered through a pipe 46 to a fuel injection nozzle 47 formed as a part of the air and fuel mixing or treating means 24. The pump 42, motor 36 and fan 33 are thus all located within the mechanical compartment 12 which has an inlet opening 48 for supplying either fresh or recirculated air to the fan 33 for delivery

to the air passages 31 and in turn to the space to be heated.

The air and fuel mixing means 24 includes a tubular housing member 49 which is closed at one end and opened at an opposite end 51 with the passage 19a (Figs. 1 and 2). A mixing chamber 52 is located at the closed end of the housing 49 and is separated from an equalizing chamber 53 by a perforated plate 54. The equalizing chamber 53 in turn is both defined and separated from the combustion chamber passage 19a by a perforated heat insulating plate 56. Extended substantially axially through the housing 49 and supported in the perforated plates 54 and 56 and projected outwardly from the closed end of the casing 49 is a combination electric heating and igniting unit 57.

The combination unit 57 includes a tubular copper sleeve 58 having an enlarged portion supported in the plates 54 and 56 for receiving in a spaced relation a resistance coil 59. The end 60 of the enlarged tube portion projects outwardly from the equalizing chamber 53 through the plate 56 and is open to the outlet end 51 of the mixing means 24. A reduced section of the sleeve 58 extends outwardly from the closed end of the casing 49 and into the air supply chamber 18. The end 60 of the reduced tube portion is closed by an insulated member 65 which carries a coil lead 70 electrically connected with one end of the coil 59. The opposite end of the coil is grounded to the tube 58 as indicated at 75. The coil 59 is wound on a mica tube 61 which has both heat and electrical insulating characteristics. In one commercial embodiment of the invention the resistance coil 59 is composed of a #20 wire capable of being heated to about 1600 degrees Fahrenheit with 12 volts at 6 amperes which temperature is capable of preparing and igniting one kind of fuel to be burned. The coil 59 is thus rather delicate and of a small size and sensitive to both operating currents and temperatures. In other words any intense heating of the coil by the flames of combustion, by accumulated generated heat within the coil due to the corroding of a portion thereof, or by a shorting out of part of the coil so that an overload current is applied on the remainder of the coil will either destroy the coil or materially reduce its heating efficiency and service life.

In the operation of the air and fuel mixing means 24 the fuel delivered to the injection nozzle 47 by the pump 42 is introduced into the mixing chamber 52, the fuel nozzle being located within the air supply chamber 18 and mounted directly on the casing 49 at the mixing chamber 52 (Fig. 2). A portion of the air for mixing with the fuel enters the nozzle 47 through ports 62 and travels with the fuel into the mixing chamber 52. Additional air to be mixed with the fuel in the mixing chamber 52 is admitted directly into the mixing chamber through apertures 63 formed in the casing 49 about the fuel injection nozzle 47. The fuel within the mixing chamber 52 is heated by the heating unit 57 and vaporized for mixing with the air in the mixing chamber. The casing 49 and the partition plate 54 are composed of a heat conducting material and are in thermal connection with the combination heating and igniting unit 57 so as to readily receive heat radiated to the tube 58 from the coil 59. The vaporous air and fuel mixture passes from the mixing chamber 52 into the equalizing chamber 53 through the perforated plate 54. The equalizing chamber 53 in cooperation with the heat insulat-

ing plate 56 acts to reduce the turbulence in the mixture and to distribute the mixture substantially uniformly over the entire cross section of the casing 49 so that a mixture of substantially uniform fuel characteristics passes through the perforated heat insulating plate 56 into the effective igniting zone of the combination unit 51.

The air and fuel introduced into the mixing chamber 52 passes about the combination unit 51 in a direction generally toward the outlet 51 of the fuel preparing means 24. After traveling through the apertured plate 56 the mixture is free to flow across the open end 64 of the tube 58 and into the effective igniting zone of the combination unit 51 adjacent the tube end 64 where it is ignited by the heated air projected from the combination unit 51, which functions in the manner explained below to discharge heated air into the fuel and air mixture. In other words, the air traversing the tube 58 is heated by the coil 59 to a temperature exceeding the ignition temperature of the fuel mixture and when projected outwardly from the end 64 of the tube 58 effects ignition of the fuel mixture.

As was previously mentioned it is desirable that any liquid or vaporous mixture be prevented from contacting the coil 59 because of the resultant injury to the coil. It is apparent, of course, that by virtue of the coil 59 being fully enclosed within the tube 58 in the mixing and equalizing chambers 52 and 53, respectively, that the mixture in these chambers only contacts the tube 58. Although the mixture about the open end 64 of the tube 58 flows generally in a direction away from the tube 58 and toward the open end 51 of the mixing means 24 any tendency of the vaporous mixture to pass through the open tube end 64 and into contact with the coil 59 is eliminated in the following manner.

The tube 58 at the junction of its enlarged and reduced sections carries an insulating supporting member 76 (Figs. 2 and 4) of substantially T-shape in cross section, with the stem portion 77 of the T being fitted within the reduced tube section and the cross arm portion 78 located within the enlarged tube section and against the shoulder formed at the junction of these two sections. The member 76 has an axial bore 79 for receiving the coil lead 10 and cooperates with the insulating member 65 to support the lead 10 in a spaced relation within the tube 58. A slot 81 extending axially the full length of the member 76 forms an air passage with the wall of the tube 58, which passage fluid connects the two sections of the tube 58. That portion of the reduced section of the tube 58, which is positioned within the air supply chamber 18, has an aperture 80 which permits air from the chamber 18 to pass through the tube 58 and outwardly from the tube at its open end 64. Since the pressure of the air in the supply chamber 18 is the only pressure which acts on the air and fuel within the mixing means 24 and to the outside of the tube 58, it is seen that a like air pressure is provided within the tube 58 which counteracts the external air pressure at the open tube end 64. As a result any tendency of the vaporous air and fuel mixture to enter the tube 58 at its open end 64 is opposed by a like pressure within the tube 58 which prevents the mixture from passing into the tube and into contact with the coil 59. It is seen, therefore, that the coil operates at all times within an air space free of any liquid or vaporized fuel. The quantity of air passing through the tube 58 is such as not to appreciably

cool the coil 59 but is sufficient to maintain an air pressure within the coil which is at least equal to the pressure acting on the air and fuel mixture at the open tube end 64. This air mixes with the vaporous air and fuel mixture adjacent the tube end 64 and is burned with the mixture in the combustion chamber 13. The flow of air through the tube 58 and the flow of the mixture through the mixing means 24 in a direction toward the outlet 51 carries the ignited mixture into the combustion chamber 13 and out of the mixing means 24 so that the coil is not exposed to the flames of combustion.

From a consideration of the above description it is seen that the invention provides an apparatus for preparing and igniting a liquid fuel for burning in which an electrical heating element, used for heating the liquid fuel to at least a vaporizing temperature for mixing with air and for igniting the vaporous mixture for combustion, is always out of contact with any portion of the liquid fuel and air and fuel mixture. The heating element is located in a tube having an air flow therethrough and operates at all times in an air space so as to be entirely free of any corroding action by the fuel. The heating element is thus able to operate over a prolonged service life with maximum efficiency.

Although the invention has been described and illustrated with respect to a preferred embodiment it is to be understood that it is not to be so limited since modifications and changes can be made which are within the fully intended scope of the invention as defined by the appended claims.

I claim:

1. In internal combustion heating apparatus which is provided with means defining a combustion chamber, a fuel and air mixing unit opening into said combustion chamber and means operative to pass fuel and air through said unit to said chamber, electrical heating means open to said combustion chamber but removed from the combustion zone therewithin and positioned to preheat the fuel and air during its passage through said unit into said combustion chamber, and means for circulating air about said heating means out of contact with said air and fuel mixture and for discharging the air into the mixture adjacent the point of delivery of the mixture to said combustion chamber whereby the circulated air is heated to a temperature above the ignition temperature of the mixture and effects ignition of the mixture upon contacting said mixture at a point removed from said heating means.

2. In internal combustion heating apparatus which includes means defining a combustion chamber and means defining an air pressure chamber adjacent one wall of said combustion chamber; a fuel and air mixing unit disposed in said pressure chamber and provided with an outer tubular member communicating with said pressure chamber and having an outlet end opening into said combustion chamber, an inner tubular member disposed within said outer tubular member to provide a space therebetween, means for moving fuel and air through said space into said combustion chamber, said inner tubular member having an end communicating with said combustion chamber adjacent the outlet end of said outer tubular member and an opposite end communicating with said pressure chamber, whereby air may flow from said pressure chamber through said inner tubular member to mix with

the fuel and air mixture at the outlet end of said outer tubular member, and means including an electrical heating element disposed within said inner tubular member to preheat the fuel and air mixture during its passage through said space and to heat the air traversing said inner tubular member to a temperature exceeding the ignition temperature of the fuel and air mixture traversing the outlet end of said outer tubular member.

3. Apparatus for preparing and igniting a combustible fuel for burning, including air and fuel mixing means having an outlet, a combination heating and ignition unit in said mixing means including a hollow member having an open end adjacent said outlet, an electrical heating element within said hollow member having one end adjacent the open end of said hollow member, a portion of the heat from said heating element being radiated to said hollow member to preheat the fuel and air in said mixing means, means directing the flow of fuel and air mixture about the open end of said hollow member and in a direction generally toward said outlet, means for transmitting air through said hollow member about said heating element and for discharging the air into the fuel and air mixture at the open end of said hollow member, and means including said heating element for heating the air to a temperature above the ignition temperature of the mixture as it passes through said hollow member, whereby ignition of the mixture at a point removed from said heating element is effected by the heated air.

4. Apparatus for preparing liquid fuel for burning, including air and fuel mixing means provided with an air and fuel mixing chamber having an outlet, a heating unit in said mixing means including hollow heat conducting means open to said outlet, means for moving air and fuel through said chamber for discharge through said outlet, an electrical heating element in said hol-

low means, the heat developed by said heating element being radiated to said hollow means to heat and vaporize the fuel for mixing with the air during passage of the air and fuel through said chamber, means for transmitting air through said hollow means in contact with said heating element and for discharging the transmitted air into the vaporous mixture adjacent said outlet, and means including said heating element for heating the air transmitted through said hollow means to a temperature above the ignition temperature of the vaporous mixture, whereby ignition of the vaporous mixture is produced by the heated air upon intermixture thereof.

10 5. Apparatus for preparing and igniting a liquid fuel for burning, comprising air and fuel mixing means having an outlet, a combination heating and ignition unit in said mixing means including a tubular member extending through said mixing means and provided with one open end adjacent said outlet and an opposite end open to the outside of said mixing means, means for moving air and fuel through said mixing means and about said tubular member in a direction from said opposite end of said tubular member toward said outlet, a portion of the heat developed by said heating element heating said air and fuel during passage of said fuel and air through said mixing means and about said tubular member, means for transmitting air into said tubular member at said opposite end for passage into the vaporous mixture adjacent said outlet, and means including said heating element for heating the transmitted air to a temperature above the ignition temperature of the mixture during its passage through said tubular member, thereby to effect ignition of the mixture by contact of the heated air with the mixture at a point removed from said heating element.
